Ball shown on webpage: <http://web.archive.org/web/20051224055635/http://www.newhorizonssoccer.com/products/1765-mini.jpg>. Display Date: Dec. 24, 2005; Retrieval Date Feb. 17, 2007.

Sportime(R) Fall 2003 Catalog, p. 248: balls A-D on lower left.

Primary Examiner—Catherine Tuttle*(74) Attorney, Agent, or Firm*—Banner & Witcoff, Ltd.(57) **CLAIM**

The ornamental design for a ball, as shown and described.

DESCRIPTION

FIG. 1 is a front right perspective view of a ball showing my new design;

FIG. 2 is a rear left perspective view of the ball in FIG. 1;

FIG. 3 is a front view of the ball in FIG. 1;

FIG. 4 is a rear view of the ball in FIG. 1;

FIG. 5 is a left view of the ball in FIG. 1;

FIG. 6 is a right view of the ball in FIG. 1;

FIG. 7 is a top view of the ball in FIG. 1; and,

FIG. 8 is a bottom view of the ball in FIG. 1.

The grayscale shading represents a contrast in either grayscale tone or color consonant with the visual appearance shown in the drawings.
